(57) **CLAIM**

The ornamental design for an orthogonal packaging material dispenser, as shown and described.

DESCRIPTION

FIG. 1 is a perspective rear view of an orthogonal packaging material dispenser in accordance with our new design;

FIG. 2 is a front elevation view thereof;

FIG. 3 is a side elevation view thereof;

FIG. 4 is a rear elevation view thereof;

FIG. 5 is a rear perspective view thereof;

FIG. 6 is a bottom front perspective view thereof;

FIG. 7 is a bottom elevation view thereof;

FIG. 8 is a bottom rear perspective view thereof; and,

FIG. 9 is a front side elevation view thereof.

It is contemplated that other embodiments of the design may include any part, portion, element, or any combination thereof shown in the figures. It is specifically contemplated that any and all solid lines and portions thereof may be converted to broken lines, whether in a subsequent divisional or continuation application and/or by amendment. In the drawings, the broken lines depict portions of the article that form no part of the claimed design.
